UNITED STATES PATENT OFFICE.

CLEMENS HERSCHEL, OF GLENRIDGE, NEW JERSEY.

MEANS FOR DRIVING HYDRAULIC TURBINES.

No. 873,435.

Specification of Letters Patent.

Patented Dec. 10, 1907.

Application filed April 26, 1907. Serial No. 370,456.

To all whom it may concern:

Be it known that I, CLEMENS HERSCHEL, a citizen of the United States, residing in Glenridge in the county of Essex and State 5 of New Jersey, have invented certain new and useful Improvements in Means for Driving Hydraulic Turbines, of which the following is a specification.

The object of this invention is to increase 10 the net fall or the effective pressure acting on a turbine water wheel by applying a suction to the discharge end of the turbine. This I accomplish by causing water passing from an upper to a lower level to traverse a suction apparatus wherein a vacuum is produced, which is applied to the discharge of the turbine to accelerate the flow therethrough. Thus water may be utilized which would otherwise waste over the dam; or the 15 water available may be applied to drive fewer turbines than by the method heretofore used, thus increasing the power output of each turbine; or a combination of these 20 two methods may be applied.

According to my invention suction is applied to the discharge orifices of hydraulic turbines by an apparatus which I call a "fall 25 increaser." This acts to produce a vacuum by the flow of water through an expanding 30 cone. Such apparatus can be built of a capacity to lift a quantity of water approximately equal to that of the turbine discharge, and approximately equal in height of lift to the fall acting on the turbine, thus 35 doubling the power of the turbine and also gaining the valuable advantage of a smaller weight of wheels and size of wheel-pit per horse power, and of a higher speed than if the fall-increaser were not used, an advantage which is of special importance in the 40 frequent cases of turbines used to drive electrical generators by direct connection.

The accompanying drawings illustrate an embodiment of the invention.

Figure 1 is a plan of a turbine installation 45 on the down-stream side of a dam; Fig. 2 is a section on the line 2—2 of Fig. 1; Fig. 3 is a section on the line 3—3 of Fig. 1; Fig. 4 shows a part of Fig. 2 on a larger scale. Fig. 50 5 is a vertical section showing a simplified form of the apparatus.

Referring to the embodiment of the invention illustrated, the dam A holds back a body of water B; the overflow from which

spills over the spill-way C to the water level 55 D below. In Figs. 2 and 3 are indicated the approximate variations in level of the two bodies of water.

The power-house E is shown as containing, for example, four electric generators F 60 operated by direct connection with four turbines G. Each turbine receives water from a penstock H and discharges through a draft tube J. According to the heretofore-accepted method, the draft tubes would freely discharge into a tail-race K. But according to my invention the discharge orifices of the turbines are connected through any suitable conduit such as that shown at L to the fall 65 increaser or suction apparatus. The preferred form of such apparatus comprises a conduit M leading from the head-water B and discharging into the tail-water K. This conduit, at a suitable point in its length, is contracted to form a throat P, and from this 70 throat to the outlet it is gradually expanded forming a cone O. Communication is made between the throat P and the suction conduit L in any manner whereby the vacuum 75 created in the throat by the flow through the increasing section of the tube or cone O is communicated through the conduit L to the discharge orifices of the turbines.

In the construction shown the conduit M expands from its inlet a to a point b forming 80 an up-stream cone S; and contracts from b to the throat P forming an intermediate cone T; and from the throat it again expands to the outlet c forming the down-stream cone O. Surrounding the throat P is an annular vacuum-chamber Q which communicates through 85 a branch with the conduit L. Connection is made between the chamber Q and the interior of the throat by a suitable number and size of holes through the tube or wall of the 90 throat.

The operating water enters at a under the head available at the dam, or wherever the fall-increaser may be set. The entrance is regulated to introduce the proper quantity 100 of water by providing an adequate size for the opening a and by the provision of a gate or valve R shown as a wicket gate revolving on a diametrical axis, and controlled by an accessible handle or gear at the top. With the expanding cone S, the water in passing from a to b loses velocity and is uniformly distributed over the cross-section a to b; from

b to the up-stream end of the throat P the velocity of the operating water is increased to the proper throat velocity while maintaining its uniform distribution. The use of 5 the expanding and contracting cones S and T is optional, it being only essential to provide a suitable volume of water passing through the contracted throat with sufficient velocity. In the construction shown a 10 means for regulating the volume and distribution of the water traversing the throat is provided, consisting of a central tube U (cylindrical or conical) fixed concentrically in the cone T, its down-stream end coming adjacent to the throat, and its up-stream end being furnished with a valve or wicket gate V, or with any suitable means for symmetrically controlling the flow of water through the tube U whereby to control the volume of 15 water passing through the throat. Whatever be the specific construction of the conduit M, the essential operation is that the water flowing through this conduit creates a sucking action in the throat which draws 20 water from the suction conduit L and the sum of this water and the operating water flows from the throat through the main suction cone O of the increaser which expands to the outlet. The sucking action is due 25 both to the contracted throat and to the expanding cone. The property of such a gradually expanding tube is that it causes an effective and powerful suction at the throat which, acting through the holes thereat, will 30 efficaciously exhaust the discharge of the turbine or turbines to which the increaser 35 may be applied.

Fig. 5 shows a fall increaser reduced to its simple and elementary form, H being the 40 penstock, G the turbine, L the turbine discharge, M the fall increaser conduit, P the contracted throat of the latter, O the expanding cone, and Q the vacuum chamber surrounding the throat P. The volume of 45 water flowing through the fall increaser is controlled by a suitable valve or gate R at the admission end a. The fall-increaser may be variously proportioned and applied. For example it may, with low falls, be made to 50 double approximately the fall which would otherwise act upon the turbines. Under suitable conditions the fall may be increased by an effective fall of some 25 ft. I have in experiments with large tubes (in one case 55 one foot and in another nine feet in diameter at the outlet) obtained a vacuum equal to 25.5 feet of water column at the throat of such tubes. Such increasers may be used merely to remove the effects of backwater, 60 during floods, by passing some of the water otherwise wasting over the dam through such increasers. But a still greater service may be rendered by them, by their doubling approximately the fall acting on the turbine

wheels to be set, throughout the year; thus 65 prescribing the setting of approximately only half the number of turbine wheels which would otherwise become necessary, and producing a materially greater speed on the turbine main shafts of the lesser number of turbines to be set, as well as reducing the size 70 and weight per horse-power of these turbines, and the size of the wheel-pit and powerhouse needed; all with approximately the same discharge of water from the upper into 75 the tail-water level.

Although I have shown several turbines and several fall increasers connected through a suction conduit L, it is nevertheless to be understood that one or any greater number 80 of turbines may be combined with one or any greater number of fall increasers; and that the turbines may be set as close to the vacuum chamber of the fall increasers as is practicable, or may be removed to any desirable distance therefrom, as local conditions will prescribe. The increaser may be built of concrete, brick, wood, or other material, with the finer parts at and adjacent to the throat of metal. My invention renders it unnecessary to carry the discharge tubes J from the turbines into the tail-race K; but to provide against the possibility of any derangement of the fall increaser, it is desirable to carry the discharge tubes J into 95 the tail-race and to provide means for ordinarily closing their communication therewith but which in an emergency, may be opened to discharge directly into the tail-race. For this purpose the tubes J may be 100 closed at their lower ends by a valve or gate N. A similar gate may be applied as shown at W for closing communication from the conduit L to each of the fall-increasers.

I am aware that it has been proposed to 105 increase the power of a turbine by diverting some of the water which would otherwise pass through it from the penstock, and carrying this water through a by-pass around the turbine and discharging it into the discharge tube after the manner of an ejector, whereby it was expected that the water thus diverted would become more effective in its 110 action upon the turbine than if it had been passed through the turbine in the usual way. 115 By my system I divert no water out of the penstock which feeds the turbine, and pass through this penstock only water intended to pass through the turbine; and I utilize surplus water which would otherwise go to 120 waste by passing it through a separate channel or pipe wherein it is caused to generate a vacuum, which vacuum is applied to and connected with the discharge outlet of the turbine, so as to apply thereto a certain 125 measure of suction, thus producing an acceleration of flow, and consequently the same increase of power generated by the turbine,

as would accompany an increase of fall represented by the amount of vacuum applied; which is thus added to the natural fall, being the difference between the level of water at 5 the dam, and that at the tail-race. By my invention this vacuum is created not by any mere induction action such as occurs when one stream of fluid flows against another, but by utilizing the negative pressure produced 10 by the flow of water through an expanding conduit under a considerable velocity head and at a low static head. This result is accomplished in my fall-increaser by applying a vacuum chamber around the throat of 15 the suction conduit, such chamber communicating with said throat by numerous orifices through which the water drawn from the turbine is sucked into the throat.

The low efficiency of ejector devices operating by the induction of one stream flowing against another, renders them unsuitable in my opinion to the production of a vacuum on the discharge side of a turbine, for the purpose of increasing the power thereof. 20 The adequate efficiency of my fall increaser for this purpose, on the other hand, is due in part to its being fed independently of the penstock, so that it does not diminish the efficiency of the turbine, by diverting water 25 therefrom; and in part to the method followed of providing a vacuum box, of creating a vacuum in it, and of then allowing the turbine to discharge into this vacuum; and I form the vacuum referred to, by passing 30 water through a suitably contracted throat, which communicates by orifices of suitable arrangement and sufficient area with the vacuum box, whence is drawn into it, by the suction created in the expanding cone, the 35 entire volume of water discharged from the turbine and any air that may accompany it. Thus the vacuum which results from the 40 expansion of the flow through the expanding cone, is directly communicated to the discharge from the turbine, with the same effect 45 thereon as if the turbine were set in a situation affording a fall greater than that actually existing, by an amount equal to the degree of vacuum created, expressed in feet 50 of water column.

What I claim is:—

1. The combination of an elevated body or source of water, a turbine, a penstock leading from the former to the latter, and a 55 fall-increaser consisting of a conduit separate from said penstock through which water may flow independently from said source to a lower level, said conduit comprising a contracted portion or throat and an expanding 60 portion or cone extending thence toward the outlet, said throat having substantially continuous walls formed with suction orifices and a suction connection communicating from said orifices to the discharge of the tur-

bine, whereby the vacuum created in said fall-increaser is transmitted to the turbine with the effect of increasing the fall acting thereon.

2. As a means of counteracting the effect on a turbine of back-water during freshets, 70 the combination with a dam forming an elevated body or source of water, a penstock and turbine, of a fall-increaser consisting of a conduit separate from said penstock through which water may flow independently from said source to a lower level, said conduit comprising a contracted portion or throat and an expanding portion or cone extending thence 75 toward the outlet, said throat having substantially continuous walls formed with suction orifices, and a suction connection communicating from said orifices to the discharge of the turbine, and means for controlling the flow through said conduit, whereby during high water surplus water 80 otherwise wasted over the spillway can be turned through said conduit with the effect of increasing the fall acting on the turbine, and compensating for the diminution of fall 85 due to back water.

3. The combination with a turbine, of a fall-increaser consisting of a conduit through which water may pass from a higher to a lower level, said conduit expanding from its contracted portion or throat toward the outlet, said throat having substantially continuous walls formed with suction orifices a 90 vacuum chamber communicating with said orifices, and a suction connection between the discharge of the turbine and said vacuum 95 chamber.

4. The combination with a turbine and its penstock, of a vacuum chamber into which the turbine discharges and a conduit through which water may pass from a higher to a lower level comprising a contracted throat 100 passing through said vacuum chamber and having orifices communicating therewith, and said conduit expanding from said throat toward the outlet, whereby is generated a 105 suction causing the water to flow at accelerated velocity through said throat and creating and maintaining a vacuum in said vacuum chamber.

5. The combination with a turbine, of a fall-increaser consisting of a conduit through which water may pass from a higher to a lower level, said conduit expanding from its contracted portion or throat toward the outlet, said throat having substantially continuous walls formed with suction orifices a 110 vacuum chamber surrounding said throat and communicating with it through said orifices, and a suction connection between the discharge of the turbine and said vacuum 115 chamber, and means for controlling the flow of water through said fall increaser.

6. The combination with a turbine of a

fall-increaser consisting of a conduit through which water may flow from a higher to a lower level, contracted to form a throat and expanded from said throat to the outlet, and 5 an inner tube mounted concentrically in said conduit on the up-stream side of the throat and terminating adjacent thereto, and means for controlling the flow of water through said tube, and a suction connection

from said throat to the discharge of the turbine.

In witness whereof, I have hereunto signed my name in the presence of two subscribing witnesses.

CLEMENS HERSCHEL.
